UNITED STATES PATENT OFFICE.

CHARLES CLEMENT KROUSE, OF WILLIAMSPORT, PENNSYLVANIA.

DEGREASING APPARATUS.

1,338,308.

Specification of Letters Patent. Patented Apr. 27, 1920.

Application filed January 27, 1920. Serial No. 354,399.

To all whom it may concern:

Be it known that I, CHARLES C. KROUSE, a citizen of the United States, and a resident of Williamsport, in the county of Lycoming and State of Pennsylvania, have invented 5 certain new and useful Improvements in Degreasing Apparatus, of which the following is a specification.

My present invention relates to an improved apparatus for degreasing hides and skins and is intended more especially for carrying out the method which forms the subject of an application filed by me in the United States Patent Office on the 20th day 15 of June, 1919, Serial No. 305,460.

The invention aims to provide a simple, economical and efficient apparatus by which the hides and skins may be easily handled and effectually subjected to the degreasing 20 operation.

In the drawings:

Figure 1 is a diagrammatic view of the entire apparatus with the treating chamber shown in section; and

25 Fig. 2 is an enlarged vertical section through a part of the treating chamber at right angles to the section shown in Fig. 1.

The treating chamber *a* is provided with top and bottom headers *b*. Connecting these 30 headers is a series of hollow plates *c*, the interiors of which communicate with the headers *b*. The headers may be conveniently formed of abutting sections, each section being integral with one of the hollow 35 plates, as shown in Fig. 2.

The plates *c* are strung on supporting rods *d*. Each plate *c* is provided on opposite sides with runways *d*. The skins are adapted to be stretched on and secured to 40 wire frames *e* having flanges *f* adapted to slide on the runways *d*. Each frame is thus adapted to be positioned between two adjacent hollow plates *c*.

The headers *b* are connected to a circulating pipe *b'* in which is interposed a tank *g* and a pump *i*. In the tank *g* water is heated by means of steam admitted through a pipe *h*. The pump *i* establishes a circulation of water through the hollow plates *c*.

50 The frames *e* are slidable in and out through the front of the treating chamber, which is adapted to be closed by means of a hinged door *j*, which is held closed so as to be air tight by means of appropriate securing devices *k*.

The interior of the treating chamber is connected, by means of a pipe *m* with a vacuum condenser *n*, which in turn is connected, by means of pipes *o* and *p*, with two drip tanks *r* and *s*, one to receive condensed water and the other condensed degreasing solvent, which may be assumed to be naphtha. These tanks are both connected, through branches of a pipe *u*, with a vacuum pump *t*.

60 The naphtha drain tank is connected through a pipe *v* with a naphtha storage tank *w*. A pipe *v* connects the storage tank, through pipe *x*, with the interior of the treating chamber.

A still *y* communicates with the interior of the treating chamber by a pipe *y'*, and, through a condenser *z*, with the naphtha storage tank *w* by pipes *z'* and *n'*.

70 The pipes are all suitably valved to control the flow of air, water and solvent.

In carrying out my process, I proceed preferably as follows. I first cleanse the skins by the usual method of washing or soaking. If received in the hair, bristles, 80 or short wool, I then depilate them by immersion or drumming in a sodium sulfid solution which causes the hair to dissolve, after which they are again washed in water to free them from the sodium sulfid. Other 85 methods of depilation may be used, for instance, a paste mixture of lime and sodium sulfid spread upon the hair which dissolves it, followed by a washing. The usual method of liming for depilation may be employed if desired.

90 The skins *q* are secured to the frames *e*, which are then slid into the treating chamber *a*. Water is circulated through the hollow plates *c* to maintain a temperature of 95 say 100° F., or well under the melting point of the collagen of the skins.

Before, after, or concurrently with establishing the said water circulation, air is evacuated from the treating chamber 100 through pipe *u*, tank *r*, pipe *o*, condenser *n* and pipe *m*, to about 29 inches of vacuum. The water in the skins boils out and the vapor passes to the condenser *n* and thence to the drip tank *r*. This treatment is preferably continued until substantially all the water is removed from the skins, which will require two hours, more or less.

105 The interior of the treating chamber is then opened to the naphtha storage reservoir 110

w, the solvent flowing into the chamber, by reason of the vacuum therein, and filling the same, it being preferable to maintain the temperature at say 100° F. The solvent 5 penetrates the dehydrated skins and dissolves the grease. The solution of solvent and grease is allowed to drain off into the still.

The vacuum, if it has been broken, is re-created. The residual solvent is then vaporized by means of vacuum and a temperature below the melting point of collagen. The vapor passes through pipe *m* to condenser *n*. The condensed liquid flows thence into the 15 drain tank *s*, from which it may be withdrawn into the naphtha storage tank *w*.

Repetition of the solvent treatment is permissible, but ordinarily unnecessary.

The skins are now thoroughly degreased 20 and in condition for tanning.

It will be obvious that a series of treatment tanks may be connected up in a suit-

able manner to increase the capacity of the apparatus and enable one or more tanks to be used for dehydrating, while another tank 25 or tanks are being used for grease extraction.

Having thus described my invention, what I claim is:

Apparatus for degreasing hides and skins 30 comprising a closed solution tank having a closure at one side, parallel hollow spaced heating elements located in said tank with means for supplying heating fluid thereto, guides arranged between said heating elements, reticulated supporting frames for the hides and skins to which said hides and skins are clamped, liquid supply and withdrawal means connected with said tank, and vacuum producing means connected with 35 40 said tank.

In testimony whereof I affix my signature.

CHARLES CLEMENT KROUSE.
